UNITED STATES PATENT OFFICE

HARRY E. WILLIAMS, OF OLEAN, NEW YORK

MATRIX ASSEMBLY FOR TYPESETTING MACHINES

Application filed March 7, 1932. Serial No. 597,333.

This invention relates to a matrix assembly designed primarily for use in connection with the typesetting sticks of machines of the "Ludlow" type wherein metal is cast on the 5 faces of the assembled matrices.

In machines of the class mentioned it has been the practice to use sticks of two different sizes, one being adapted for holding $\frac{7}{8}$ " matrices while the other is for holding $1\frac{1}{4}$ " 10 matrices. All of the slugs for use in each stick have been made of a size adapted to that stick. This has been true of matrices for use in casting type of maximum sizes as well as type of smaller sizes and, in order that the 15 smaller type might be printed in different positions relative to the base line of the larger type, additional matrices have been required for the different positions. For example, one 20 matrix has been required for use in casting a small letter "a" on the base line occupied by the large letter or letters associated therewith. Another matrix has been required for casting the letter "a" at a point midway between the 25 base and the top lines of the associated large letter or letters, and a third matrix has been necessary for casting the type "a" on a line with the top of the large letter or letters. Obviously this has required a varied assortment 30 of matrices and has added to the time and labor involved in properly setting the matrices in the stick or sticks.

It is an object of the present invention to provide a means whereby small matrix slugs can be supported in a stick designed for holding large matrix slugs, these added means being utilized for maintaining the small slugs or slug at any desired positions relative to the ends of the large matrix slug so that the type 40 cast from the small matrices will be at predetermined positions relative to the type cast from the large matrices.

With the foregoing and other objects in view which will appear as the description 45 proceeds, the invention resides in the combination and arrangement of parts and in the details of construction hereinafter described and claimed, it being understood that changes in the precise embodiment of the invention 50 herein disclosed may be made within the

scope of what is claimed without departing from the spirit of the invention.

In the accompanying drawings the preferred form of the invention has been shown.

In said drawings:

Figure 1 is a bottom plan view of a large stick with which are assembled matrix slugs of different sizes, by the use of the present improvement.

Figure 2 is a top plan view.

Figure 3 is a section on line 3-3, Figure 1.

Figure 4 is a section on line 4-4, Figure 1.

Figure 5 is a section on line 5-5, Figure 1.

Figure 6 is a section on line 6-6, Figure 1.

Figure 7 is a section on line 7-7, Figure 1.

Figure 8 is a section on line 8-8, Figure 1.

Figure 9 is a face view of a stereotype cast from the matrices shown in Figure 2.

Figure 10 is an end elevation thereof.

Referring to the figures by characters of reference, 1 designates a stick of the type used in the "Ludlow" machine for holding $1\frac{1}{4}$ " matrix slugs. This stick has a clamping block 2 slidable in one end and adapted to be actuated by a screw 3 extending from either end 75 of the stick. The stick differs from the ordinary ones employed, in that grooves 4 are extended longitudinally within the top face thereof adjacent to the upper and lower walls of space 5 into which the slugs are insertible. 80

The stick illustrated is of the $1\frac{1}{4}$ " size for holding matrix slugs and quads of the $1\frac{1}{4}$ " size. One of the large size quads has been illustrated at 7 in Figure 8 and is provided with the usual terminal lugs 7 adapted to 85 overlie the stick 1 when the quad is dropped into the space 5. It is to be understood that the large size matrix slugs are to be similarly made although none of them have been shown 90 in the drawings.

The small size slugs to be used in a $\frac{7}{8}$ " stick are of the same general contour as the large size quads and slugs, and have been illustrated at 8. These are formed with terminal lugs 9 which, in a small size stick, 95 would overlie the surface of the stick in the same manner as illustrated by the large size quad in Figure 8.

In order that the small slugs and quads can be supported properly in the large stick 100 I

have devised filler slugs 10 and 11 of two different sizes. The filler slugs 10 are twice the size of the filler slugs 11 and each of them has a recess 12 providing a seat 13 for one of the lugs 9. Each filler slug 10 has a projecting lug 14 for overlying the stick and from this lug 14 depends a lip 15 adapted to project into the adjacent groove 4. Where large filler slugs 10 are employed the small matrix slugs can be supported at either the top or the bottom of the space 5. In the drawings matrix slugs for casting type "\$125.50" have been shown positioned adjacent to the upper side of the space 5 while the large filler slugs 10 have been interposed between the lower side of the space 5 and the matrix slugs. In assembling these slugs 8 and 10 the filler slugs 10 are first inserted into the inverted stick 1 at the proper points so that lips 15 will enter the adjacent groove 4. Thus the filler slugs will be properly held against displacement and the space left between them and the far side of the space 5 will be such as to receive the small slugs 8. One lug 9 of each of these slugs will rest on the stick, as shown in Figures 3, 4, and 5, while the other lug 9 will rest on the seat 13 provided therefor by the filler slug.

Where narrow matrix slugs of the small size are used, as shown for example at 16, a single filler slug 17 can be used in connection with all of them and with one or more quads 18 of the smaller size. Filler slug 17 is of the same contour as the slug 10 and differs therefrom solely in its length which can be suited to the number of slugs 16 and 18 with which it is to be used. Obviously there is no limitation as to the length of the filler slugs employed.

Should it be desired to support the small size matrix slugs in intermediate positions, as shown for example at 19 in Figures 2, 6 and 7, it would then be necessary to use two of the smaller or half-size filler slugs 11. These half-size filler slugs are also recessed to provide seats 20 and have lugs 21 from which depend lips 22. The half-size filler slugs are inserted in the space 5 at the top and bottom thereof so that the lips 22 will enter grooves 4 at the proper points. Thus the filler slugs will be properly supported and a small size slug 19 can then be dropped into the space between these slugs 11 with its terminal lugs 9 resting on the seats 20. As a result of this arrangement the small matrix slugs will be held centered in the space 5 provided for large matrix slugs. After the various matrix slugs, filler slugs and quads, both large and small, have been assembled in the stick they are all pressed together tightly by means of block 2 and screw 3 and thereafter a type 23 is cast on the mat faces of the slugs and subsequently can be used for printing purposes.

Although no 1 1/4" matrix slugs have been illustrated, it is to be understood that they

can be assembled with the smaller matrix slugs should such a type combination be desired.

By using one size stick for both sizes of slugs considerable time and labor is saved in assembling the slugs in a machine of the "Ludlow" type.

What is claimed is:

1. A matrix assembly including a stick having a slug receiving space, a filler slug in said space, means on the slug for engaging the stick to detachably support the slug, and a seat on said slug below the upper face thereof for engaging a portion of an undersize matrix slug when inserted into said space and supporting the matrix slug with its upper face substantially flush with the upper face of the filler slug. 75

2. A matrix assembly including a stick having a slug receiving space and a groove, 85 a filler slug insertible in the space and having a seat, and means on the slug for engagement in the groove to hold the slug assembled with the stick, said seat constituting a support for a portion of a matrix slug insertible into said space. 90

3. A matrix assembly including a stick having a slug receiving space and a groove, 95 a filler slug insertible in the space and having a seat, and means on the slug for engagement in the groove to hold the slug assembled with the stick, and a slug insertible into and removable from said stick independently of the filler slug, said seat constituting a support for a portion of the inserted slug. 100

4. In a matrix assembly a stick having a slug receiving space and grooves near opposed portions of the space, a filler slug insertible into the space, and means thereon for engaging in either groove to support the slug against one wall of the space, said slug having a seat for engagement by a matrix slug or the like insertible into the space. 105

5. In a matrix assembly a stick having a slug receiving space and grooves near opposed portions of the space, opposed filler slugs insertible in said space, means thereon for engaging in the grooves to removably support the slugs against opposite walls respectively of said space, said slugs having seats, and a slug insertible into the space between the filler slugs for engagement with the seats for support thereby, said supported slugs being removable independently of the filler slugs. 110 115 120

In testimony that I claim the foregoing as my own, I have hereto affixed my signature.

HARRY E. WILLIAMS.
